UNITED STATES PATENT OFFICE.

SAMUEL BOORN, OF LOWELL, MASSACHUSETTS.

IMPROVEMENT IN LOOMS.

Specification forming part of Letters Patent No. 35,918, dated July 22, 1862.

To all whom it may concern:

Be it known that I, SAMUEL BOORN, of Lowell, in the county of Middlesex and State of Massachusetts, have invented an Improved Cushion-Case to be applied to a Shuttle-Box of a Loom for Weaving; and I do hereby declare the same to be fully described in the following specification, and represented in the accompanying drawings, of which—

Figure 1 denotes a side elevation, Fig. 2 a rear end view, Fig. 3 a bottom view, and Fig. 4 a horizontal section, of it as provided with a cushion formed of layers of leather, caoutchouc, and curled horse-hair.

The nature of my invention consists in an improved metallic case for an elastic cushion to be employed upon the shuttle-box of a loom, in order to prevent violent concussions and injury to the picker or picker-staff.

In the drawings, A denotes the body of the said case, within which I form a socket or chamber, B, for reception of an elastic cushion, E. The said case I form with a wide notch or recess, b, arranged in it, as shown in the drawings, the same being for the purpose not only of allowing the said cushion to expand laterally, but of preventing injury to the neck of the picker, such as would result by the said neck repeatedly striking against the edge of the metallic case, as it would do were there no such notch and the cushion should settle within the case. Furthermore, through the rear part of the case I make two rectangular or other proper shaped slots, c c', for reception, respectively, of the two end portions of a band or strap, f, which is employed to secure together and in place the component parts of the cushion. The elastic material or cushion, having been inserted in the said socket B, should be confined therein by means of the said band, which for such purpose should be looped on

the cushion and be drawn tightly through such slots, and may be wedged or fastened therein.

C is a cylindrical hole carried longitudinally through the said case, such hole being for the reception of the race-rod of the picker. The said case, when placed upon such rod, is to be confined thereto by means of a set-screw, D, the same being as shown in Fig. 2.

I would remark that I do not limit my invention to the precise form of picker-case as represented in the accompanying drawings, as I intend to vary the same as circumstances may require, while I do not change its character or the nature of my improvement. Furthermore, I would remark that the width of the mouth or entrance of the notch b should be somewhat greater than that of the neck or part of the picker which is to enter the notch, and such notch should be so arranged in the side of the cushion-case that when the said case is in place on the loom the picker or the picker-staff, as the case may be, when striking the cushion may enter the notch without coming in contact with either of the sides or bottom thereof.

I do not claim a simple box or cushion-case; but

What I do claim is—

1. My improved loom-picker cushion-case as made with a notch or recess, b, arranged with reference to its cushion and for reception of the picker or picker-staff, in manner and for the purpose substantially as specified.

2. The cushion-case as provided or made with the loop-slots extending through its bottom or rear part and out of its cushion-chamber, in manner and for the purpose as described.

SAMUEL BOORN.
